WRENCH

Filed April 15, 1926

FIG. 1.

IT. 2

TIT. 3.

BY

INVENTOR
JAMES DICKIE

Yesterdaysology
ATTYS.

UNITED STATES PATENT OFFICE.

JAMES DICKIE, OF BERWICK, NOVA SCOTIA, CANADA, ASSIGNOR OF TWO-THIRDS TO
WILLIS I. HUNTLEY AND PERRY BORDEN, OF NOVA SCOTIA, CANADA.

WRENCH.

Application filed April 15, 1926. Serial No. 102,255.

This invention relates to improvements in wrenches, and the object of the invention is to provide a wrench that can be instantly changed to fit any sized nut, whereby when used by mechanics and others more satisfactory and quicker results are obtained than with wrenches at present in use.

The invention consists in the combination with a wrench, of a plurality of adjustable 10 filler blades pivotally mounted in the handle of the wrench and designed in operation to engage with and restrict the recesses formed in the wrench whereby the latter is automatically adjusted to fit nuts of different 15 sizes.

Referring now to the drawings in which like characters of reference indicate corresponding parts in each figure,

Fig. 1 is a side view of my improved 20 wrench with the filler blades mostly in inoperative position,

Fig. 2 is a plan view showing the filler blades opened out,

Fig. 3 is a section on line 3—3 of Fig. 1,

Fig. 4 is a perspective detail of one of the 25 filler blades, and

Fig. 5 is a section on the line 5—5 of Fig. 1.

Referring now more particularly to the 30 drawings, in which a preferred example of my invention is illustrated, 10 designates an ordinary wrench as a whole, provided with recesses 11 and 12 of different dimensions at each end, the ends as is well known being 35 enlarged as at 13 and 14, and the intermediate body portion 15 forming the handle portion for the wrench.

Adjacent the recesses 11 and 12 and in the 40 body portion are slots 16 and 17 spaced from said recesses by solid intervening portions 18 and 19.

Within these slots, pivotally mounted on pins 20, are a plurality of filler blades 21, adapted in inoperative position to lie snugly 45 within the slots and, as illustrated in Fig. 1, flush with the surface of the body portion. These filler blades are provided with recesses or cutouts 22 designed to engage with the shoulder or bridge portions 18 and 19 enabling the blades to fit snugly, as also illustrated in Fig. 1, in the recesses 11 and 12 50 to automatically curtail their size and there-

by adapting them to fit bolt nuts of different sizes. According to the size of the nut, one or more of the blades 21 may be employed. 55

For swinging the blades into operative position I provide thumbnail spaces or recesses 23 in the sides of the wrench. The outer ends 24 of the blades are preferably slanted to engage with the slanting ends 25 60 of the recesses 16 and 17 in inoperative position and thus limit the travel of the blades beyond a predetermined point.

From the foregoing the operation of my 65 wrench will be apparent, as in order to adjust it to fit any size of nut it is only necessary to swing as many of the blades 21 as may be necessary to form a clamping means for the nut from their inoperative position into one of the end recesses 11 and 12. 70

As many changes could be made in the above construction and many apparently widely different embodiments of my invention, within the scope of the claims, constructed without departing from the spirit 75 or scope thereof, it is intended that all matter contained in the present specification and accompanying drawings shall be interpreted in an illustrative and not in a limiting sense. 80

What I claim as my invention is:

1. A wrench comprising a body portion recessed at one end, intermediately and centrally slotted, a plurality of filler blades pivotally mounted in said body adjacent to the recess and formed on the under side with 85 recesses to engage with the body, said blades being adapted to be moved selectively and collectively to render the wrench adjustable and to fit flush with the surface of the 90 wrench.

2. The combination with a slotted wrench or spanner provided with enlarged portions at each end, one of said enlarged portions being partially cut out or recessed, a plurality of blades formed on the under side 95 with recesses pivotally mounted in said slot and adapted to swing across and engage with the recessed enlarged portion to adjust the size of the wrench and to swing in the opposite direction flush with the surface of the 100 wrench.

In witness whereof I have hereunto set my hand.

JAMES DICKIE.
